UNITED STATES PATENT OFFICE

162,112

EXHAUST TAIL PIPE EXTENSION

Albert D. Baker, Lansing, Mich., assignor to General Motors Corporation, Detroit, Mich., a corporation of Delaware

Application July 29, 1950, Serial No. 11,472

Term of patent 3½ years

(Cl. D14—6)

To all whom it may concern:

Be it known that I, Albert D. Baker, a citizen of the United States, being a resident of Lansing, State of Michigan, have invented a new, original, and ornamental Design for an Exhaust Tail Pipe Extension, of which the following is a specification, reference being made to the accompanying drawing, forming a part thereof.

In the drawing:

Figure 1 is a perspective view of an exhaust tail pipe extension, showing my invention.

Figure 2 is a side elevational view thereof.

Figure 3 is a bottom plan view thereof.

Figure 4 is a rear end elevational view.

I claim:

The ornamental design for an exhaust tail pipe extension, substantially as shown.

ALBERT D. BAKER.
